Primary Examiner — Karen E Kearney*(74) Attorney, Agent, or Firm* — Banner & Witcoff, Ltd.(57) **CLAIM**

The ornamental design for a display screen with graphical user interface, as shown and described.

DESCRIPTION

FIG. 1 is a front view of a display screen with graphical user interface showing our new design;

FIG. 2 is a front view of a display screen with graphical user interface showing the design of FIG. 1 with an additional uneven broken line;

FIG. 3 is a front view of a display screen with graphical user interface showing an alternative embodiment of our new design; and,

FIG. 4 is a front view of a display screen with graphical user interface showing the design of FIG. 3 with an additional uneven broken line.

The broken line showing of the text, the humanoid figure, remainder of the user interface, and the remainder of the display screen is for environmental purposes only and forms no part of the claimed design. The uneven broken lines in FIGS. 2 and 4 also form no part of the claimed design.
